UNITED STATES PATENT OFFICE.

DAVID F. FELTEN, OF ROSEDALE, KANSAS.

AIRSHIP.

1,091,315.

Specification of Letters Patent. Patented Mar. 24, 1914.

Application filed November 22, 1912. Serial No. 732,916.

To all whom it may concern:

Be it known that I, DAVID F. FELTEN, a citizen of the United States, residing at Rosedale, in the county of Wyandotte and 5 State of Kansas, have invented new and useful Improvements in Airships, of which the following is a specification.

This invention relates to airships, the object of the invention being to provide an 10 aerial vessel which affords speed, safety and steadiness in flight, which is adapted to ascend or descend in a direct line and to hover at any desired point in the air, which is adapted to automatically maintain its 15 equilibrium, and which, in the event of the stoppage of its driving power, will descend safely to the ground.

The invention consists of the features of construction, combination and arrangement 20 of parts hereinafter fully described and claimed, reference being had to the accompanying drawings, in which:—

Figure 1 is a side elevation of an airship embodying my invention. Fig. 2 is a top 25 plan view of the same. Fig. 3 is a central vertical longitudinal section through the airship. Fig. 4 is a fragmentary vertical section on an enlarged scale through the upper portion of the mast, lifting and sustaining 30 propeller and associated parts. Fig. 5 is a similar section taken at right angles to the plane of the section shown in Fig. 4. Fig. 6 is a detail sectional elevation of the means for varying the working angle of the blades 35 of the lifting and sustaining propeller. Fig. 7 is a detail sectional view showing one of the clutch connections between a gear and its shaft. Fig. 8 is a top plan view of the shutter and governor controlling the air 40 vents in the parachute plane. Fig. 9 is a view of the wind-brake, showing in full and dotted lines the vanes thereof in folded and spread condition. Fig. 10 is a vertical transverse section through the mast showing 45 the lateral steering propellers and gearing therefor. Fig. 11 is a detail section showing the clutch connection between certain parts of the drive gearing.

Referring to the drawings, 1 designates a 50 car or coach of streamline form, designed to accommodate the aeronaut and passengers, if any, and also to contain the driving motor 2, which car or coach is shown in the present instance as provided with tapered bow 55 and stern portions 3 and 4. Rising from the car or coach is a hollow mast 5 carrying

at its upper end a combined supporting and lifting surface, consisting of a dished or inverted saucer-shaped body or plane 6 and a propeller 7 arranged to rotate about the 60 same.

The plane 6 may be rotatably mounted, but as shown is preferably fixed to the upper end of the mast and carries at its lower edge an externally grooved track rim or rail 8. 65 The propeller 7 comprises a pair of spaced concentric rings 9 and 10 suitably connected and reinforced by spokes or arms 11 and between which is arranged an annular series of blades 12 pivotally mounted to swing 70 vertically on trunnions or axes 13, by which the working angle of the blades may be regulated and varied as occasion may require.

The ring 10 is annularly grooved to form, 75 in conjunction with the grooved rim 8, a raceway in which are arranged antifriction bearings 14, permitting the propeller 7 to revolve at high speed with a minimum of frictional resistance. At their normal working angle the propeller blades 12 are adapted 80 in conjunction with the plane 6 to sustain the machine in the air, and by increasing or decreasing their angle of incidence the machine may be propelled upwardly to any 85 desired altitude or permitted to descend slowly to the ground. It will thus be seen that either by regulating the speed of motion of the propeller or varying the angle of incidence of its blades, the ship may be caused to 90 ascend or descend in a substantially vertical path or sustained and caused to hover at a fixed point above the earth's surface, the advantages of which will be apparent.

Surrounding the plane 6 is a grooved 95 ring 15, forming a track receiving friction rolls 16 on crank arms 17 connected with the propeller blades 12. The inner face of said ring 15 is provided at intervals with pairs of diagonal ribs forming inclined grooves 100 18 receiving supporting pins or projections 19 extending from the plane 6, said grooves and pins acting as cams whereby when the ring is turned in one direction it will be elevated and when turned in the opposite 105 direction will be depressed, thus swinging the blades 12 either upwardly or downwardly on their axes to increase or decrease their angle of incidence. A rock shaft 20 is journaled on the mast and carries at its 110 outer end a slotted crank arm 21 engaging a pin 22 on the ring 15, whereby the latter

may be shifted. Said shaft is also provided on its inclosed portion with a crank arm 23 coupled by a link or other connection 24 extending downwardly through the mast with 5 a controlling lever 25 arranged within the car, whereby the aeronaut may shift the ring to adjust the blades 12 as occasion requires.

The plane 6 and propeller 7, when the 10 ship is in flight, rest upon a compressed body of air beneath the same, and thus form a surface which operates both as a sustaining and a propelling medium. The propeller 7, which is stayed by braces 26 from 15 a rotary collar 27 carried by the mast, is propelled in a clockwise direction from the motor 2 by pinions 28 in gear with the ring 10 and carried by transmission shafts 29 extending radially from the hollow mast 20 and journaled in suitable bearings on the mast and plane 6. The inner ends of the shafts carry bevel pinions 30 meshing with a bevel gear 31 on the upper end of a vertical driving shaft 32 extending longitudinally 25 within the mast, whereby the series of shafts 29 may be simultaneously operated to drive the propeller. At its lower end the shaft 32 carries a bevel drive gear 33 meshing with a similar gear 34 on a countershaft 35 suitably driven from the motor 2, as by 30 a chain or belt connection 36.

The gear 33 is loose on the shaft 32 and carries a pivoted dog or pawl 37 having a weighted outer end connected by a coiled 35 contractile spring with the gear, the toothed end of said dog being adapted to engage a ratchet wheel 38 fixed to said shaft. The gear 33 is normally driven from the motor through the gear 34 in a counter-clock-wise 40 direction and when said gear 33 is so driven the weighted end of the dog 37 is thrown outward by centrifugal force against the resistance of the contractile spring, whereby the toothed end of the dog is held in engagement 45 with the teeth of the ratchet wheel, whereby the shaft 32 is driven in a counter-clock-wise direction, such direction being considered from the viewpoint of the aviator in the direction of flight. The clutch 50 connection between the gear 33 and shaft 32 thus provided, however, will permit the shaft 32 to be driven independently of the gear 33 in a clock-wise direction, such action being permitted by reason of the fact 55 that in such motion of the shaft the gear 33 remains inactive and the contractile spring acting on the dog 37 holds the dog out of engagement with the teeth of the ratchet wheel.

60 The plane 6 is designed by its form and in connection with the parachute 7 to serve as a parachute to insure the safe descent of the machine to the ground in the event of the stoppage of the motor or damage to the 65 drive gearing. For this purpose said plane

is provided with one or more air vents 39. In the present instance a series of air vents, four in number, are shown, arranged at the front, rear and opposite sides of the center of the plane, and at least one of which vents 70 is constantly open for the escape of excess air pressure, so that under any and all conditions when a contingency arises a parachutic action will be automatically established when the ship falls a determined distance. The use of a series of vents 39 enables an automatic stabilizing action to be obtained by means of a gravity controlled stabilizing device comprising a collar or sleeve 40 journaled to freely rotate on anti-friction bearings about the upper end of the mast and carrying a series of disks or shutters 41 and a weighted arm or lever 42. The disks are less in number by one than the vents 39, and are arranged so as to partially 80 or wholly cover any three of the vents at a time to regulate the escape of air therethrough, leaving the remaining vent open for a parachutic action whenever necessity arises. When the ship tilts either in a fore 85 and aft or a lateral direction, the weighted arm 42 turns toward the down tilted side and in so doing shifts the shutters so that the opening at that side will be covered to prevent the escape of air therethrough, while the 90 opening at the high side will be uncovered to permit the escape of air therethrough, thus controlling the supporting action so as to automatically maintain the equilibrium 95 of the ship.

100 Arranged below the plane 6 is a collar or sleeve 43 which rotates about the mast on antifriction bearings 44 and is provided with a beveled gear 45 meshing with similar gears 46 on the shafts 29. The said collar or sleeve 43 carries a propeller 47, the blades of which are pitched to give a lifting and sustaining action when said propeller is revolved in a clockwise direction. Each gear 46 is loosely mounted on its shaft 29, but is 105 provided with a spring actuated dog or pawl 48 to engage a ratchet wheel 49 on said shaft. When the shaft 32 is driven positively by the motor and turns the shafts 29, the ratchet wheels 49 slide over the pawls 48, the gears 46 thus remaining fixed when the wheel 7 is positively driven in a clockwise direction, so that in normal condition 110 of service the propeller 47 is inactive. When the motor stops and the machine begins to descend, a parachutic action is established to arrest its speed of descent and at the same time the action of the air on the blades 12 causes the wheel 7 to revolve as a windmill in a counterclockwise direction, 115 thus turning the shafts 29 in the contrary direction to their normal direction of motion. By this means the gears 46 are fixed by the pawl and ratchet clutch devices to 120 said shafts 29 and thereby transmit motion 125 to said shafts 29 and thereby transmit motion 130

to the propeller 47, which acts in conjunction with the parachute plane and propeller 7 to sustain the greater proportion of the weight of the machine as it descends, allowing it to descend slowly and safely to the ground. The speed of descent of the ship under these conditions may obviously be controlled by adjusting the blades 12. On its reverse motion in which it is driven by the wind wheel action of the propeller 7, the shaft 32 turns independently of the gear 33, through its described clutch connection therewith.

Disposed below the propeller 47 and at the front or rear of the mast is a driving propeller 50, the shaft 51 of which is journaled upon the mast and has its inner end extending thereto and provided with a bevel gear 52. This gear 52 is adapted to mesh with either of a pair of gears 53 and 54 on a sleeve 55 feathered to the shaft 32 and adjustable by means of a lever 56 to shift either the gear 53 or the gear 54 into mesh with the gear 52. In normal service and when the shaft 32 is driven by the motor and it is desired to drive the ship ahead, the gear 53 is shifted into engagement with the gear 52 whereby driving motion is imparted to the propeller. When, however, the motor is thrown out of action or accidentally stops and the shaft 32 is driven on the descent of the machine by the counterclockwise wind wheel motion of the propeller 7, the gear 54 may be shifted into engagement with the gear 52 to communicate driving motion to the propeller 50 whenever it is desired to propel the machine ahead in order to clear obstacles in the path of the machine in its descent or to enable it to be landed at any certain point. The lever 56 is coupled by a connection 57 with a control lever 58 in the car, whereby the sleeve 55 may be shifted either upwardly or downwardly.

Arranged at any suitable point between the supporting surface and car and on opposite sides of the mast 5 are steering or controlling propellers 59 and 60, the shafts 61 and 62 of which are journaled upon and extend at their inner ends into the mast 50 and carry bevel gears 63 and 64 which are adapted to mesh with a gear 65 carried by a sleeve 66 feathered to the shaft 32, whereby said gear 65, which is normally disposed in an intermediate or inactive position, may be adjusted to throw either of the steering propellers into action to propel the machine laterally in one direction or the other. These propellers may be employed in conjunction with the vertical rudders for a quick steering action or simply to secure a sidewise movement of the ship without a turning movement, in order that obstacles may be passed or the ship steered without loss of headway or creating objectionable head resistance, the advantages of which

will be readily understood. The sleeve 66 is adjustable by means of a lever 67 coupled by a connection 68 to a controlling lever 69 within the car. The several levers 25, 58 and 69 may be provided with pawls or dogs 70 to engage rack segments, whereby they may be secured in adjusted position.

Supported upon the mast is a vertical rudder 70 adapted to be operated by cables 71 passing over suitable guides to a controlling device, not shown, in the car. Also supported by the mast is a wind-brake comprising a pair of pivoted laterally swinging vanes 72 which normally stand in a folded, edgewise or non-opposing position, but are adapted to be swung outwardly in opposite directions at right angles to the line of flight, as indicated in dotted lines in Fig. 9, to oppose a resistance to the motion of the machine in order that the speed of motion of the machine may be checked and the machine brought to a quick stop and rapidly controlled under various conditions of service. The vanes 72 are connected by links 73 with a pneumatic operating device comprising a cylinder 74 containing a piston whose rod 75 is coupled directly to the links. The cylinder may be supplied with fluid pressure in any suitable manner to spread or retract the vanes as will be readily understood.

From the foregoing description, it will be seen that my invention provides an airship which in flight and in its launching and landing operations rests upon a body of compressed air which supports it and enables it to sustain itself and to ascend or descend without the necessity of gliding over and successively compressing new bodies of air or traveling in its launching and landing operation in an inclined plane, as is necessary in the operation of flying machines of the aeroplane type. It will also be seen that the invention provides an airship which may be readily controlled and which embodies safety factors of great advantage and importance. It will, of course, be understood that friction gearing may be substituted if desired for the bevel gearing disclosed, and that other changes and modifications may be made within the spirit and scope of the invention as defined in the appended claims.

I claim:

1. In an airship, a car, a mast rising therefrom, a supporting surface carried by the mast and comprising a parachute plane and a propeller rotating therearound, said plane having a series of openings and said propeller having blades adjustable to vary their angle of incidence, a gravity controlled automatically movable controlling member provided with shutters governing the openings in the plane, and means for adjusting the propeller blades.
2. In an airship, a car, a mast rising

therefrom, a motor, a supporting surface comprising a plane and a propeller rotating therearound, a lifting propeller, and gearing for driving the first named propeller from the motor, said gearing being operative to drive the lifting propeller upon a retrograde rotation of the supporting propeller when the motor stops.

3. In an airship, a car, a mast rising 10 therefrom, a motor, a supporting surface comprising a plane and a propeller revolvable about the same, said propeller adapted to be positively driven in one direction and to revolve by air pressure when the machine 15 falls in the reverse direction, a lifting propeller, and gearing between the motor and supporting propeller and between the latter and the lifting propeller, for independently operating the supporting propeller from the 20 motor and operating the lifting propeller from the supporting propeller when said lifting propeller revolves in an opposite direction to its normal direction of revolution.

4. In an airship, a rotary lifting and 25 sustaining propeller, a second lifting propeller, said lifting and sustaining propeller being adapted to be positively driven in one direction and to be rotated by air pressure in the opposite direction, a motor, gearing 30 between the motor and the lifting and sustaining propeller and between the latter and the second lifting propeller, said gearing including a shaft revolvable in opposite directions respectively, under the action of the 35 motor and the lifting and sustaining prop-

peller, a driving propeller, and means for driving the same from said shaft in either direction of revolution of the latter.

5. In an airship, a car, a mast rising 40 therefrom, a parachute plane supported by the mast, a lifting and sustaining propeller revolvable about said plane, said propeller being revolvable in a retrograde direction by air pressure in the descent of the ship, gearing for positively driving said propeller, a 45 motor for driving said gearing, a second lifting and sustaining propeller, gearing for driving the same through the first named gearing from the first named lifting and sustaining propeller when the latter revolves 50 in a retrograde direction, a driving propeller, and means for operating the same through the first named gearing in either direction of motion of the first named lifting and sustaining propeller. 55

6. In an airship, a dished supporting surface having openings therein, a propeller rotating around said supporting surface, a mast carrying the supporting surface and propeller, a gravity controlled member revolvable about said mast, and shutters carried by said member and controlling said openings in the supporting surface. 60

In testimony whereof I affix my signature in presence of two witnesses.

DAVID F. FELTEN.
